LAPIDARY MOUNTING

George Jacobi and David Jacobi, Mount Vernon, N.Y.

Application June 18, 1959, Serial No. 56,412

Term of patent 14 years

(Cl. D45—19)

FIG. 1

FIG. 2

Fig. 1 is a plan view of our lapidary mounting; and Fig. 2 is a sectional view taken in the plane 2—2 of Fig. 1 and in the direction indicated by the arrows, to show the surface configuration of the same.

The characteristic feature of our invention resides in horizontal and vertical bands superimposed on a heart shaped base, contained in a heart shape frame mounting wherein the bands are inlaid one on the other, and on the base, to provide a smooth surface of bands and base.

We claim:

The ornamental design for a lapidary mounting, as shown and described.
